Specification for Design.

Patented Oct. 4, 1921.

Application filed October 27, 1920. Serial No. 420,028. Term of patent 14 years.

To all whom it may concern:

Be it known that we, LEE B. JONES, EARL W. JONES, and ROBERT G. BATTIN, citizens of the United States, residing at Evansville, in the county of Vanderburg and State of Indiana, have invented a new, original, and ornamental Design for Power Plants, of which the following is a specification, reference being had to the accompanying drawing, forming a part of this specification.

Figure 1 is a view taken from the side of a power plant embodying our design;

Fig. 2 is a perspective view taken from the

near left hand corner of the plant shown in Fig. 1; and,

Fig. 3 is a perspective view taken from the far right hand corner of the plant shown in Fig. 1.

We claim:

The ornamental design for a power plant, as shown.

In witness whereof we have hereunto subscribed our names.

LEE B. JONES.
EARL W. JONES.
ROBERT G. BATTIN.
